PROTECTIVE ARTICLE OF MANUFACTURE

Ralph A. Farnham, Herkimer, N. Y.

Application April 3, 1936, Serial No. 72,516

2 Claims. (Cl. 229—6)

This invention relates to a class of articles which can be styled as comprising protective devices for fragile articles. Specific examples of such devices are flats and holders for packaging and protecting eggs, pads to line the sides of cartons, protectors for electric light bulbs, radio tubes, etc., flats, trays, holders and protectors for bottles. Numerous other such articles are known to those experienced in the art.

10 In particular, the object of the present invention is to devise an article of the class described which may be divided into a plurality of sections with a minimum of effort and risk of destruction, but which is sufficiently rigid to be manufactured, 15 sold and used in a standard size comprising a plurality of separable sections. Particular uses for the invention are as follows:

1. Egg protectors are usually desired in a size capable of protecting one dozen eggs. With the 20 present invention a protector for holding one dozen eggs is provided which can be separated into two protectors, each capable of protecting six eggs, thereby providing the egg dealer with both sizes in the one lot which may be supplied 25 to him.

2. Pads for lining the insides of cartons are usually of a specified size, for instance, of a size 30 to fit snugly against one wall of a carton capable of holding one dozen bulbs to be protected. With the present invention such a pad may be supplied which is, nevertheless, capable of being separated into a plurality of sections, each of a size to line the wall of a carton capable of holding a smaller 35 number of bulbs.

3. Other protective articles of any sort desired may be so divided, the above examples being illustrative and not by way of limitation; and it is apparent that the invention can be applied in 40 such a manner as to provide an article capable of separation into more than two smaller articles.

Other objects and advantages flowing out of the present invention are as follows:

1. The elimination of various sizes of moulds 45 or other mechanism to produce various sizes of articles.

2. The reduction of various sizes of shipping packages of the articles to one standard size, thereby simplifying the shipment of articles from 50 the plant to the consumer.

3. The reduction of inventory labor and storage space.

Other and further objects and advantages will be apparent from the following description taken 55 in connection with the accompanying claims and

the drawing wherein like numerals refer to like parts throughout.

Referring to the drawing there is illustrated the following:

Fig. 1 is a plan view of the type of egg protector 5 fully disclosed and claimed in the patent to Morris Koppelman, No. 1,746,838, issued February 11, 1930, having the present invention applied thereto;

Fig. 2 is a plan view of a type of egg protector 10 similar to that disclosed and claimed in the patent to John Harvey Pickett, No. 1,967,040, dated July 17, 1934, having the present invention applied thereto;

Fig. 3 is a plan view of a carton liner of the 15 type disclosed and claimed in the patent to Fred D. Gray, No. 1,808,136, dated June 2, 1931, having the present invention applied thereto;

Fig. 4 is a partial cross-section taken on line 4—4 of Fig. 3 and showing details on an enlarged 20 scale; and

Fig. 5 is a view in perspective of an article made in accordance with the present invention, showing its utility and advantages when in use.

The articles to which the present invention is 25 applied are articles made from fibrous materials, such as ground wood, reclaimed newspapers, etc., which are usually moulded on foraminous moulds, usually by a suction process on machines such as disclosed in the patent to Ellis C. Healy, No. 1,967,361, dated July 24, 1934. The method of incorporating my improvement into the articles and the apparatus for performing the same are disclosed in my copending application, filed of even date herewith.

35 The process of moulding such articles comprises the felting of individual fibres into a flexible, but practically self-sustaining form by interlacing or felting the fibres into a layer of substantially uniform thickness deposited upon the surface of the mould. The articles are then removed from the mould and subjected to the action of heat, (other steps possibly being performed as is well known in the art) whereby a relatively dry, completed article is produced.

40 The use of the equipment described and claimed in my aforesaid pending application results in the production of an article having the objects and advantages above described, the article provided with weakened areas along which the article may be separated, the weakened areas comprising portions capable of permitting the desired results.

45 Fig. 1 discloses the W-shaped type of egg protector disclosed in Patent No. 1,746,838, in which 55

opposed pockets 11 are provided in pairs, each pair designed to hold an egg. The article as manufactured comprises two sections, 12 and 13, of similar nature, capable of being separated 5 from each other along a line of weakened areas 14. It is, of course, to be appreciated that the weakened areas 14 could be contiguous across the article, but I prefer spacing separate weakened areas by non-weakened areas of such small 10 extent that the division of the article into sections is not hindered, but sufficient in extent to brace the article when used in non-separated form. The edge of the article may be provided with notches 15 and openings 16 in line with the 15 weakened areas 14 which would make the tearing of the article into two parts easier to accomplish and which would result in opposite ends of the two parts being substantially similar in appearance.

20 Fig. 2 discloses at 20 the type of holder found in Patent No. 1,967,040, provided with pockets 21 in four rows of pockets. The article is adapted to fold upon itself whereby to bring the first and second rows into complementary relation with 25 the fourth and third rows, respectively, each complementing pair of pockets being designed to protect an egg. The article is capable of use, as shown, to protect a dozen eggs, but may be divided into sections of similar nature, 22 and 23, 30 by separating the same along the line of weakened areas 24.

Fig. 3, shows at 30 a carton pad consisting of a generally planiform sheet provided with protuberances 31 which are designed to protect the 35 contents of the carton from shock. This form of article may likewise be separated into similar sections 32 and 33 along the line of weakened areas 34.

It will be observed with respect to each article 40 illustrated that it is divided into sections in a manner similar to each of the other articles by a line of weakened areas extending along at least one edge of each section. It is obvious that were the articles to be divided into more than 45 two sections, there would be connecting, weakened areas along more than one edge. It is also to be observed in the views that each article can be divided by a continuous weakened area, but that each article is preferably formed with 50 spaced, weakened areas for the purpose described in connection with areas 14 of Fig. 1. A further point of similarity is that the weakened areas preferably extend to notches 25 at the edge of the article, so that the point at which tearing 55 would begin, were the article to be divided, is weaker than the immediately adjacent portions of the edge of the article, and may be provided with an opening 26 in order that opposite ends of the two sections would be similar.

60 Fig. 4 is a view taken on line 4-4 of Fig. 3 (which is, of course, identical to views which could be taken across the weakened areas 14 of Fig. 1 or the weakened areas 24 of Fig. 2) and showing the weakened areas 34 in enlarged cross-section. In this view of the article is shown as comprising felted, fibrous material 40 of substantially uniform thickness throughout. The weakened area 34 comprises felted fibres formed into a relatively thin layer 41 extending between 65 the sections 32 and 33 at one side of the article. In the preferred form as illustrated, projections of felted fibres 42 extend from the other side of the article, forming between themselves and the layer 41 a slot or groove 43 extending substantially the thickness of the article. The method

of forming the articles is such that the main body of the article is necessarily formed of felted fibres 44 interlaced into a sheet of substantially uniform density. The uniform density of formation is preserved throughout the layer 41 and 5 the extensions 42, whereby the advantages of my invention are achieved.

Fig. 5 illustrates one manner in which the article 10 of Fig. 1 may be used. The article 10 is folded into W-shape, eggs are inserted into 10 the pockets, and the loaded article is inserted lengthwise into a sleeve 50. The sleeve is representative and the article may be placed in other types of wrappers, cartons, or the like, each designed snugly to hold the article and the enclosed eggs. The result is a package of protected eggs which may be sold as a unit. However, it is common throughout the trade to provide sleeves, cartons, etc., with a line of perforations encircling the carton, sleeve, etc., as at 52. In 20 this manner the sleeve, carton, etc., may be broken into two parts, each designed to receive smaller holders and half a dozen eggs. Herefore the smaller holders were supplied in complete form with the attendant disadvantages 25 noted above. With my invention the package may be grasped at its end and broken into completed packages, preferably over the edge of a 30 table 51, as illustrated. If preferred, the article may be separated into its component sections 30 before it is placed in the holder or sleeve. Any article made in accordance with my invention may be separated into its parts by tearing it from edge to edge, or by breaking it as illustrated. The weakened areas likewise provide a 35 guide for bending the article so that an article such as illustrated in Fig. 3 may readily be bent into angular shape to protect more than one wall of a carton.

The invention presents great advantages over 40 prior art practices. It has been attempted to weaken articles by compressing the fibres as by rolling or stamping. This method not only required separate manipulation and mechanism, but resulted in frequent failures, since the compressed areas had the same, or possibly greater, 45 strength as the body of the article, and the sections would not separate as desired. The present invention achieves the object since the layer 41 is of the same density, but thinner than the 50 body of the article. It was likewise attempted to score the articles by means of an abrading, cutting, or perforating action. These methods likewise required additional handling and equipment and it was found that the depths of penetration, 55 and the rigidity of the article when used as a whole, could not be controlled. In the present invention, the necessary result of its manufacture is that the layer 41 is of substantially uniform fibre strength, density and thickness. A further 60 advantage which can be obtained and is preferred lies in the formation of the extensions 42, which provide, in effect, a knuckle joint strengthening the structure against ordinary bending in one direction, the side to which the extensions extend being selected as the side to be braced against ordinary failure by bending.

An unforeseen result of the use of the articles, such as the egg protectors 10 or 20 in a container such as the sleeve 50, is that exact registry of the 70 weakened areas and of the perforations in the sleeve is not required in order that the package may be broken into two parts. It is observed that the weakened areas 14 may be as much as one half of an inch out of line with the perforations 75

52 when the package is broken as described.

The illustrations of articles to which my invention is applied are obviously not to be taken as limiting the scope of my invention, since the 5 same may be applied to numerous other articles known to those skilled in the art. Various modifications in construction and arrangement will readily suggest themselves to the skilled artisan and I do not intend to be limited to the present 10 disclosure except in so far as required by the scope of the following claims.

I claim:

1. A protective article of manufacture of substantially uniform thickness made of felted, 15 fibrous material, comprising a plurality of sections of similar nature adapted to be separated from each other, the sections being defined on at least one edge by a weakened area in the article, said area comprising felted fibers forming 20 a relatively thin layer of the same density as the sections extending between sections at one side

of the article, and fibrous projections extending from the opposite side of the article along opposed edges of said weakened areas whereby partially to brace said article against bending stresses.

2. A protective article of manufacture of substantially uniform thickness made of felted, fibrous material, comprising a plurality of sections of similar nature adapted to be separated from each other, the sections being defined on 10 at least one edge by a line of spaced, weakened areas in the article, said areas comprising felted fibers forming a relatively thin layer of the same density as the sections extending between sections at one side of the article, and fibrous projections extending from the opposite side of the article along opposed edges of said weakened areas, each pair of said projections and the interposed layer defining a groove extending at least 15 partially through the plane of the article.
